UNITED STATES PATENT OFFICE.

JOSEPH JERANEK, OF NEW YORK, N. Y.

GUN-REST.

No. 879,052.

Specification of Letters Patent.

Patented Feb. 11, 1908.

Application filed October 18, 1907. Serial No. 397,978.

To all whom it may concern:

Be it known that I, JOSEPH JERANEK, a subject of the Emperor of Austria-Hungary, and a resident of the city of New York, borough of Manhattan, in the county and State of New York, have invented a new and Improved Gun-Rest, of which the following is a full, clear, and exact description.

My invention relates to gun rests, and is especially adapted for use by sharp shooters, marksmen and infantry, where very accurate shooting is essential.

An object of my invention is to provide an adjustable gun rest which can be firmly mounted upon the ground, and which presents a rigid support for the free end of a rifle or other weapon.

A further object of the invention is to provide a device of the class described adapted to be removably carried on the person of the operator and easily available for use.

The invention consists in the construction and combination of parts to be more particularly described hereinafter and particularly set forth in the claims.

Reference is to be had to the accompanying drawings forming a part of this specification, in which similar characters of reference indicate corresponding parts in all the figures, 30 in which

Figure 1 is a perspective view of my device; Fig. 2 is a longitudinal section showing the means for adjusting the height of the device; Fig. 3 is a side elevation showing my device 35 attached to a belt; Fig. 4 is a cross section showing the method of attaching my device to a belt; and Fig. 5 is a plan view showing the gun securing means and further showing in dotted outline certain parts in another 40 position.

Referring more particularly to the drawings, 1 represents a standard fashioned from any suitable metal, such as steel, aluminium, or the like, and sharpened at its lower end to 45 permit of its being inserted into the ground. The upper end of the standard bears a button or enlargement 2, integral therewith, and for a purpose to be hereinafter described. A disk 3, is mounted upon the standard and 50 serves to hold the latter in position, limiting the penetration of the standard into the earth.

Movably arranged upon the standard is a hollow or tubular support 4, which has its lower edge 5, bent inwardly to serve as a stop to the button 2 of the standard, thereby preventing the withdrawal of the standard from

the support. The lower portion of the support has a threaded opening 6, in which is mounted a set-screw 7, by means of which the support may be secured in a plurality of 60 positions. The upper portion of the support 4 may, if desired, be provided with a detachable head 8, having a threaded or other suitable connection with the support. Rotatably mounted upon this head and pivotally 65 connected thereto by means of a rivet or bolt 10, is a bracket 9. A stirrup 11 has resilient arms 12 suitably spaced for securing the free end of a gun in position, and is pivotally mounted between the sides of the bracket 9 70 by means of screws or bolts 13. The stirrup 11 may be fashioned from any suitable spring material, such as steel, brass or the like.

I provide a carrier 14 including a spring clip, the arms 16 of which serve movably to 75 hold the device. The carrier 14 has lateral flanges 15 which can be secured to a belt or other portion of the apparel of the operator by means of rivets 17.

My invention is not only useful for securing the free end of a gun in position to permit of very accurate shooting, but also on rifle ranges and the like, for mounting a gun, especially after it has been used, and allowing it to cool off evenly on all sides. When used 85 as a support in firing, the pivotal action of the bracket and the further pivotal action of the stirrup, permit of the gun being securely supported in a plurality of positions.

Having thus described my invention, I 90 claim as new and desire to secure by Letters Patent:

1. A device of the character described, comprising a standard, a support having a telescopic engagement with said standard, a 95 bracket rotatably mounted on the upper end of said standard, and a stirrup pivotally secured to the ends of said bracket and provided with inverted free ends of resilient material.

2. A device of the class described, comprising a standard provided on one end with a head, a tubular support having a telescopic engagement with said standard and provided with a contracted lower end to engage the 105 head of said standard, and serve as a stop, a bracket rotatable horizontally on said support, and a stirrup pivotally attached at its sides to the ends of said bracket and provided with inverted free ends of resilient material. 110

3. A device of the class described, comprising a standard, provided on one end with

a head, a bearing plate attached to said standard, a support having a telescopic engagement with said standard and provided with means for holding said support and standard in engagement, means attached to said support for locking the support and standard fixedly in position, a bracket rotatable horizontally on the upper end of said support, and a stirrup having its central portion shaped to conform to said bracket, its sides pivotally connected with the ends of said bracket, and inverted free ends of resilient material extending inwardly of the sides of said stirrup.

15 4. A device of the character described, comprising a standard, a support having a

telescopic engagement with said standard, a bracket rotatable horizontally on the upper end of said support, a stirrup having its sides pivoted to the ends of said bracket and provided with inverted free ends of resilient material extending inwardly of the sides of said stirrup, and a spring clip adapted to be detachably secured to said support. 20

In testimony whereof I have signed my name to this specification in the presence of two subscribing witnesses.

JOSEPH JERANEK.
